UNITED STATES PATENT OFFICE.

STERLING ELLIOTT, OF NEWTON, MASSACHUSETTS.

ADDRESSING-MACHINE.

1,210,440.

Specification of Letters Patent.

Patented Jan. 2, 1917.

Application filed January 4, 1915. Serial No. 481.

To all whom it may concern:

Be it known that I, STERLING ELLIOTT, a citizen of the United States, residing at Newton, in the county of Middlesex and State of Massachusetts, have invented an Improvement in Addressing-Machines, of which the following is a specification.

This invention relates to addressing or like machines which employ a series of address-plates or stencils adapted to coöperate with printing-devices and serve as stencil means by which addresses are printed on envelopes, bill heads and other things.

While having other and more general fields of usefulness the invention is well adapted to be embodied in an addressing machine of the type shown in my Patent No. 1,025,459, patented May 7, 1912.

A prime object of the invention is to provide improved means for reversing and re-stacking the address-plates or stencils after they have been used as by a machine of the type shown in said patent, so that they are piled or stacked in the same order as when supplied to the machine.

A further important object is to provide operating elements having a continuous rotary motion as distinguished from a reciprocating or oscillating movement, adapted to receive the address-plates or stencils as discharged successively from the machine and arrange them in a pile after turning each one over, so that they are piled in proper relation.

A further object is to provide improved means for receiving and piling the discharged stencils, wherein the same operating element, by the act of transferring a stencil from the guide-way to the stencil-receptacle, automatically reverses the stencil before it enters said receptacle, without requiring any separate elements for effecting the turning over of the stencils.

A still further object is to provide improved stencil reversing and piling means arranged underneath the stencil receptacle into which the stencils are piled, thereby making the machine shorter and more compact.

A still further object is to provide stencil reversing and piling means adapted to be geared to the other working parts of the machine so as to operate with certainty in

accurately timed relation to the rest of the machine.

55

A still further object is to provide stencil reversing and piling means having a yieldable stencil shifting element adapted to pass over a stencil that may be crumpled or mutilated, without injury to the working parts, and to again come into operative engagement with the next stencil at the proper time.

A still further object is to provide a relatively simple mechanism, that is at the same time reliable and certain in operation, for receiving the stencils as successively discharged by the machine, and piling them in proper order, so that they may be removed from the receptacle, and again used without any rearrangement.

The foregoing and other objects and features of the invention will be better understood from the following detailed description taken in connection with the accompanying drawings.

Referring to the drawings, Figure 1, is a side elevation showing my improved mechanism, the adjoining parts of the machine, and also a part of the stencil-receptacle being broken away. Fig. 2, is an end-view of the same. Fig. 3, is a transverse section approximately on line 3—3 of Fig. 1. Fig. 4, is a plan view of Fig. 1. Fig. 5, is a lengthwise vertical section on line 5—5 of Fig. 3. Fig. 6, is a sectional detail of the yielding stencil shifter.

The base 10 of the device has a receiving way at its top into which the address-plates or stencils are successively pushed from the guide-way 11 of the machine by any suitable pusher mechanism, such as shown in my said patent, where the present mechanism would replace the stencil reversing and piling mechanism shown at the right in Fig. 2. From a side of the base 10, spaced-apart curved stencil guiding-members 12 extend, constituting a guide-way for the stencils, that, starting as a continuation of the receiving-way in the base 10, curves around through substantially a semi circle as it extends upward, terminating in a compartment or receiver 13, that may be positioned directly over the base 10. The receiver 13, is shown as integral or rigid with the curved stencil guiding-members 12, and the base 10,

constituting therewith a rigid frame-work upon which is arranged the stencil-holding receptacle 14. This receptacle is shown as formed of a series of upright posts bolted 5 or otherwise secured to the receiver 13, and adapted to receive and hold the stencils as they are pressed up therewith from the receiver to form a pile or stack. The rigid frame-work formed by the base 10, guide-members 12, and receiver 13, has formed therewith, a central journal-bearing 15 for an operating-shaft 16, this journal-bearing being supported and held by ribs or struts 17, extending inwardly from the frame-work 10 members and said bearing is concentric with the curved guide-members 12. The shaft 16 may be driven by a suitable connection from the addressing-machine, so as to rotate in timed relation therewith as for example a 20 sprocket-chain (not shown) engaging a sprocket 18, on said shaft. The shaft 16 has fixed thereon a hub 19, which bears a radially extending forked shifter-member 20, the forks or fingers 21 of which engage the successive stencils, as they are pushed on to the base 10, and move them along in the curved guide-members 12 into the receiver 13, and while so moving them, turning them over into reversed position. This shifter is 30 yieldingly connected to the hub by a pivotal connection at 22, a spring 23 arranged on said pivot reacting between the hub and shifter to hold the shifter normally radial, there being a stop-shoulder 24 in rear of the pivot 35 to prevent the shifter from swinging forward beyond the radial position. The shaft 16 has fixed thereon, at opposite sides of the guide-way formed by the guide-members 12, bevel-pinions 25, that engage similar pinions 40 26, at the lower ends of shafts 27, vertically journaled in bearings 28 of the frame-work, and having at their upper ends large heads 29 with deep spiral grooves 30 therein. These heads 29, extend into the receiver 13 from each end thereof, just enough so that 45 the spiral-grooves 30, are in position to engage the ends of the stencils as they are successively moved into the receiver by the shifter 20. These grooves 30 are so arranged 50 and proportioned and the ratio of driving rotation imparted to the heads by the gearing 25, 26, is such that they are rotated to lift the stencils into the receptacle 14, in alined position to form a pile or stack, as 55 fast as presented into the receiver 13, by the shifter 20, the lower ends of said grooves being in receiving position adjacent the delivery end of the guide-members 12, each time a stencil is presented thereto by the shifter. The heads 29, have flat tops, which 60 as here shown serve as and form the bottom of the receptacle 14, upon which the pile of stencils rest, until they are removed from the receptacle. Said spirally grooved heads 65 and means for rotating them constitute lift-

ing-means for engaging the stencils in the receiver, and moving them bodily in an upward direction into the receptacle, and in lieu of the specific form of lifting-means here shown, other forms may be employed 70 which come within the spirit and scope of my invention.

The shafts 27 are continuously revolved by the shaft 16, which, in turn is continuously revolved from a suitable part of the machine, but the relation of the fingers 21 to the grooves 30 is so timed, that the fingers reach the limit of their upward travel at the moment that the lowermost portions of the grooves are rotated into the space indicated 80 by the numeral 13 in Fig. 5, so that the address-plate is transferred from said fingers to said grooves at the very moment these grooves begin their phase of effective lifting movement. The feed of the address-plates 85 along the guide-way 11, is intermittent, and both the fingers 21 and the grooves 30 have a phase of effective lifting movement extending through substantially a half revolution of the shafts 16 and 27, and a phase of non-effective return movement in the other half revolution of said shafts. 90

It will be understood that by reason of the yielding connection of the shifter 20 with the hub 19, said shifter while held in operative position, *i. e.*, substantially radial by the spring 23 in normal operation, is adapted to yield backward should it encounter a stencil that might be mutilated or crumpled, so as to pass over such stencil without injury to the parts, returning to engage the next succeeding stencil at the correct moment. It will thus be observed that the mechanism required for handling the stencils to reverse them and pile or stack them 100 in proper relation in the holder or receptacle 14 is exceptionally simple and compact, requiring only a minimum number of operating parts which have a continuous rotary motion only, the act of reversing or turning over of the stencils being carried out in a very simple manner, and as an incident to the necessary transfer of the stencils from the guideway to the holder or receptacle 105 that is to receive them. The described orbital movement of the stencils through a semi-circle from the guide-way to the holder 14 has the double advantage of providing for the reversal of the stencils in the most convenient manner and permitting the location 110 of the holder or receptacle into which they are to be received, over the end of the guide-way and the operating-mechanism, thus making the machine considerably more compact, and saving room space. By dispensing 115 with intermediate reciprocating or oscillating parts, and connecting the shaft 16 to be driven directly from the operating-mechanism of the machine, and with the operative elements driven thereby, *i. e.*, the 120

shifter 20 and the lifters 29 arranged for uni-directional and continuous rotary movement, the number of parts required is greatly reduced and the mechanism made more reliable and certain in operation.

5 While I herein describe the invention as relating to an adjunct of addressing-machines, it is to be understood that this is merely illustrative and is intended to typify any use to which the mechanism set forth 10 for reversing and stacking stencils or the like may be adapted.

I claim:—

1. In an addressing-machine, a guideway 15 along which the address-plates are moved, an upright holding receptacle mounted adjacent said guide-way, in which the address-plates are adapted to be stacked, plate-lifting means associated therewith, a plate guide 20 extending in a semicircular path from said guideway to said receptacle, to reverse the plates while the plates are being moved along said plate guide, and a shifter rotatable about an axis in parallel relation with the guideway, adapted to engage a plate on 25 the guide-way and move it along the plate guide into engagement with said lifting means.

2. In an addressing-machine, a guide-way 30 along which the address-plates are moved, a holding receptacle for the plates arranged adjacent said guide-way, plate-guiding means, a shifter associated therewith for moving the plates successively from the 35 guide-way into alining position beneath said receptacle, and reversing their position while thus moving them, and lifting-means for lifting them into the receptacle.

3. In an addressing-machine, a guide-way 40 along which the address-plates are moved, a holding receptacle for the plates arranged adjacent said guide-way, plate-guiding means, a shifter associated therewith for moving the plates successively from the 45 guide-way into alining position beneath said receptacle, and reversing their position while thus moving them, and lifting-means for lifting them into and supporting them in the receptacle.

50 4. In an addressing-machine, a guide-way along which the address-plates are moved, a holding receptacle for the plates arranged adjacent said guide-way, plate-guiding means, a shifter associated therewith for 55 moving the plates successively from the guide-way into alining position beneath said receptacle, and reversing their position while thus moving them, and lifting-means into engagement with which the plates are moved 60 by the shifter, said lifting-means being arranged to move the plates in an upward direction into the receptacle.

5. In an addressing-machine, a guide-way along which the address-plates are moved, a 65 holding receptacle for the plates arranged

adjacent said guide-way, plate-guiding means, a shifter associated therewith for moving the plates successively from the guide-way into alining position beneath said receptacle, and reversing their position while 70 thus moving them, and lifting-means into engagement with which the plates are moved by the shifter, said lifting-means being arranged to move the plates in an upward direction into the receptacle, and to support 75 them therein in alined position.

6. In an addressing-machine, a guide-way along which the address-plates are moved, a holding receptacle for the plates mounted adjacent said guide-way, plate-guiding 80 means, a shifter arranged below said receptacle and adapted to move the plates successively along said plate-guiding means from said guide-way to aline them for stacking in said receptacle, and vertically disposed ro- 85 tary means operatively connected with said shifter for engaging the plates which are delivered by said shifter and bodily lift them into said receptacle.

7. In an addressing-machine, a guide-way 90 along which the address-plates are moved, a holding receptacle for the plates mounted adjacent said guide-way, plate-guiding means, a rotary shifter coöperative therewith for moving the plates successively from 95 said guide-way to aline them for stacking in said receptacle, and vertically disposed ro- tary spiral members operatively connected with said shifter for engaging the plates which are delivered by said shifter and bod- 100 ily lift them into said receptacle.

8. In an addressing-machine, a guide-way along which the address-plates are moved, a holding receptacle for the plates mounted adjacent said guide-way, plate-guiding 105 means, a shifter coöperative therewith for moving the plates successively from said guide-way to aline them for stacking in said receptacle, and rotary spiral members having flat tops operatively connected with said shifter for engaging the plates as delivered by said shifter, and for moving them up- 110 ward into the receptacle, said flat tops sup- porting the plates in the receptacle.

9. In an addressing-machine, a guide-way 115 along which the address-plates are moved, a holding receptacle for the plates mounted adjacent said way, plate-guiding means, and a shifter coöperative therewith for mov- ing the plates from said guide-way to aline 120 them for stacking in said receptacle, said shifter having a yielding mounting adapted to permit it to pass over a plate, which unduly obstructs its movement.

10. In an addressing machine, a guide- 125 way along which the address-plates are moved, a holding receptacle for the plate mounted adjacent said guide-way, a semi- circular plate guide extending from said guide-way to the receptacle by which the 130

plates are reversed, means for moving the plates along said guide-way, means for lifting the plates into said receptacle, and operating mechanism connected to operate said 5 plate moving and plate lifting means in timed relation to the operation of the machine.

In testimony whereof I have signed my name to this specification in the presence of two subscribing witnesses.

STERLING ELLIOTT.
